UNITED STATES PATENT OFFICE.

FRANK P. WILLIAMS, OF DETROIT, MICHIGAN.

DRAG LINK FOR STEERING GEARS.

1,418,044.

Specification of Letters Patent. Patented May 30, 1922.

Application filed May 27, 1921. Serial No. 473,092.

To all whom it may concern:

Be it known that I, FRANK P. WILLIAMS, a citizen of the United States, residing at Detroit, in the county of Wayne and State 5 of Michigan, have invented certain new and useful Improvements in Drag Links for Steering Gears, of which the following is a specification.

This invention relates to drag links for 10 steering gear or the same construction can be used in the connecting link between the two arms of the steering knuckles. It is the object of the present invention to provide a link construction for steering gear which 15 can be made in the form of a stamping of triangular cross-section, thereby making for lightness of construction and economy in manufacture. These drag links are ordinarily made of seamless tube with a larger 20 tube fitted over each end to form the spring housings of the yieldable universal joints. This construction is relatively more expensive than the construction now about to be described.

25 In the drawings,—

Fig. 1 is a fragmentary elevation of the end of the drag link.

Fig. 2 is a fragmentary elevation of the other end of the drag link.

30 Fig. 3 is a section longitudinally of the drag link through either end.

Fig. 4 is a fragmentary plan view of the blank from which the stamping is made.

35 Figs. 5 and 6 are sections taken on the section line A—A of Fig. 4, showing how the metal is formed up into the tubular ends of the drag link.

Figs. 7, 8 and 9 are sections on the line B—B of Fig. 4, showing how the rod portion 40 of the drag link is formed up.

Fig. 10 is a perspective of the cap or plug for the end of the drag link.

Fig. 11 is a longitudinal section of a modified form of construction.

45 As already explained, these drag links are ordinarily made out of seamless tube. A piece of seamless tube forms the rod portion while a second piece of seamless tubing of larger diameter is fitted on the end of the 50 rod portion to form a receptacle for the rod part of the joint and spring. In place of this construction I blank out a sheet metal blank such as shown in Fig. 4. This comprises a straight strip portion *a* whichulti-

mately forms the rod portion of the link 55 and the end portions *b*. Each of these end portions is formed of a blank such as shown in Fig. 4, the cut-out recess *c* being on either side and ears *d* being at the end. This blank is then placed between suitable dies which 60 forms up the end portion in the semi-circular shape shown in Fig. 5 and the rod portion into a rectangular shape such as shown in Fig. 7. The partially formed stamping is then placed in another set of suitable dies 65 and the semi-tubular end portions are closed into a complete tube as shown in Fig. 6, while the rod-like portion is bent over into a triangular section, as shown in Fig. 8. The fold of the lock-seam *x* may then be 70 closed, as shown in Fig. 9. The two recesses *c*, *c* match together to form the slot through which engages the stem *e* that carries the ball *f*. Engaging each side of this ball is a cup *g*. One of the cups abuts 75 against the cap or plug *h* and the other is engaged by the spiral compression spring *i* which pushes against an abutment *l*.

In place of the ordinary screw plug that goes into the end of the head of the drag 80 link I can provide a plug or cap *h* which is simply a cup-like stamping provided with the perforated ears *k*. These ears *k* are adapted to fit in between the folded-over ears *d* when the plug has been inserted in 85 the tubular head *b* and turned through a part of a turn. The cotter pins *m* may then be slipped through the registering perforations of the ears to lock the cap or plug in place. This assembly may easily be made 90 after the steering gear is turned to turn the wheels around to one extreme position. This relieves the cup *g* of all stress so that no trouble will be found in assembling the cap or plug into the end of the tubular head. 95

In Fig. 11 I have shown the circular head portion of the link tapped and the usual screw plug in place. Here the cap *h* is used simply as a lock nut.

The triangular section for the rod portion 100 of the link makes the rod portion of the rod stronger so far as bending stresses are concerned for obviously it presents two walls widthwise to almost any bending stress, hence is considerably stronger than tube. 105 The triangular form may also be easily formed up by dies and folded over into the lock seam as shown in Figs. 7-9. However,

other means for making the seam can be used and still come within the purview of my invention. The head portions *b* of the link are shown seamed together by welding but 5 obviously other ways might be adopted.

The same construction may also be used between the two steering knuckle arms to 10 form the connecting link, hence in the claims I use a title of broader import than "drag link". In some cars there is a universal joint and spring abutment at only one end, hence in the claims reference is made to 15 only one end of the link.

In some of the claims I have referred to 20 the head portion of the drag link as a tubular head. It will be understood that I use tubular in the broader significance of a body having a closed hollow cross section which may vary somewhat from the true cylindrical shape without altering the functions and 25 the features of the structure.

What I claim is:

1. A link for use in motor vehicle steering gear, comprising a single piece stamping 25 formed up to provide a rod portion having a closed but hollow section and an integral tubular head portion at the end and of larger diameter.

2. A link for use in motor vehicle steering 30 gear, comprising a single piece stamping formed into a rod portion of triangular cross section lock-seamed together and an integral tubular end portion of greater diameter.

3. A link for use in motor vehicle steering 35 gear, comprising a single stamping formed into a rod portion having a closed but hollow cross section and an end or head portion of tubular shape with recesses in opposite sides of the stamping at the head portion to form 40 the opening for the stem and ball of the joint.

4. A link for use in motor vehicle steering 45 gear, comprising a single piece formed into a rod portion of closed but hollow cross section and a head portion of tubular charac-

ter the edges of the piece being secured together.

5. A link for use in motor vehicle steering gear, comprising a single stamping formed 50 into a rod portion having a polygonal section and an end or head portion of tubular form, said stamping having edges meeting and folded together.

6. A link for use in motor vehicle steering gear, comprising a flat blank formed up 55 into a rod portion and a head portion, each of hollow cross section, said head portion having projecting ears, and a cap fitting into the end of the head portion and provided with ears to register with the ears of 60 the head portion and which may be removably secured to such ears of the head portion.

7. A link for use in motor vehicle steering gear, comprising a blank formed up into 65 a rod portion and a head portion of hollow cross section, said head portion having projecting perforated ears, and a cap in the form of a stamping adapted to be fitted into the end of the head portion and provided 70 with projecting ears having perforations, the ears of the cap and the head registering, and cotter pins passing through the perforations in said ears to lock the cap into the head.

8. A link for use in motor vehicle steering 75 gear, comprising a blank formed up into a rod portion and a head portion, each of hollow cross section, the head portion being provided with projecting perforated ears 80 folded back upon themselves, and a cap provided with ears projecting from the end of the same, said cap adapted to be fitted into the head with the ears engaging between the folds of the ears of the head, and means 85 passing through the folded ears and the ears of the cap for removably securing the cap in the head.

In testimony whereof I affix my signature.

FRANK P. WILLIAMS.
